DESIGN FOR A SCRAPER

Edward L. Jones, Evanston, Ill.

Application February 1, 1940, Serial No. 89,927

Term of patent 14 years

To all whom it may concern:

Be it known that I, Edward L. Jones, a citizen of the United States, residing at Evanston, in the county of Cook and State of Illinois, have invented a new, original, and ornamental Design for a Scraper, of which the following is a specification, reference being had to the accompanying drawing, forming a part thereof.

In the drawing:

I claim:

The ornamental design for a scraper, substantially as shown.

EDWARD L. JONES.
